UNITED STATES PATENT OFFICE.

MATTHIAS GATES, OF WICHITA, KANSAS.

ADJUSTABLE MITER-BEVEL.

SPECIFICATION forming part of Letters Patent No. 392,508, dated November 6, 1888.

Application filed July 10, 1888. Serial No. 279,551. (No model.)

To all whom it may concern:

Be it known that I, MATTHIAS GATES, a citizen of the United States, and a resident of Wichita, in the county of Sedgwick and State of Kansas, have invented certain new and useful Improvements in Adjustable Miter-Bevels; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a representation of my invention and is a side view thereof. Fig. 2 is a side view with bevel-blade removed. Fig. 3 is a side view showing miter-flanges. Fig. 4 is a perspective, and Fig. 5 is a detail.

The invention relates to improvements in miter-bevels; and it consists in the construction and novel arrangements of parts as hereinafter set forth.

25 The object is to provide a convenient tool so arranged and graduated that the bevel-blade may be easily and accurately adjusted to the proper inclination for marking a rafter or other timber to be beveled at the ends.

30 Referring to the drawings, A designates the stock, preferably having one of its edges faced with metal, as at a. The metal facing near one end has the laterally-projecting lug a', which is designed as a bearing.

35 B is a try-square blade rigidly fixed in the kerf b at one end of the stock.

C C' represent the clamping-jaws for the bevel-blade D, the inner one, C, being rigidly secured to the stock by means of screws, and the outer one, C', being removably placed on one side of the blade and on the raised transverse strip b'. A lug, c', on the strip b' enters a notch in the removable jaw and serves to prevent it from turning.

45 E is a thumb screw for clamping the jaws tightly on the bevel-blade. Each jaw is provided with a laterally-projecting miter-plate, E', one of which is designed as a marker to the right and the other to the left.

50 F is an arc recess in the jaw C, within which

the arc fulcrum-plate G is designed to move. A rib, e, on the arc fulcrum is adapted to enter the longitudinal slot e' in the bevel-blade D, so that the said blade may be adjusted lengthwise.

The lug f on the jaw C is designed as a stop for the bevel-blade. When the edge of the blade bears against the lug, the said blade is at right angles to the stock and may be then used as a try-square.

One edge of the jaw C' is transversely beveled and provided with graduating or scale marks which extend over the front face of the jaw, as at f', and are numbered for a purpose hereinafter explained. The scale g on the 65 beveled edge of the jaw is divided into sixteenths, by means of which the fall or pitch of a door or window sill may be ascertained or described—that is, the bevel-blade placed at the first mark on the scale will indicate a fall 70 of one inch to the foot.

The openings h through the try-square blade and the bevel-blade enable the mechanic to obtain any width of groove or rabbet for window or door cap or staircase at the same time 75 the square and bevel are determined and marked.

It will be observed that the scale-marks on the face of the jaws C are numbered 6-12, 12-6, 8-12, 12-8, and 12-12, and the method of operation may be illustrated as follows:

To mark off the ends of the rafters for a roof having one-fourth pitch, the inner edge of the bevel-blade is placed at the mark numbered 6-12, which gives the bevel for the top 85 end of the rafter. Then move the blade to 12-6 to mark the bevel at the foot of the rafter.

Having described my invention, what I claim is—

1. In combination with the stock, the try-square blade having the rabbet-marking openings, substantially as specified.

2. The combination, with the stock, of the jaws having the right and left laterally-projecting miter-markers, substantially as specified.

3. The combination, with the stock, of the fixed jaws, the removable jaw, the arc fulcrum, the bevel-blade, and the try-square blade, substantially as specified.

4. The combination, with the stock, of the fixed jaw having the laterally-projecting miter-plate, the removable jaw having the miter-plate, the clamping-screw, the arc recess in 5 the fixed jaw, the fulcrum-plate having the rib moving therein, and the bevel-blade having the longitudinal slot to engage the said rib, substantially as specified.
5. A bevel having pitch-graduating marks

thereon and the rabbet-marking openings in to the blade, substantially as specified.

In testimony whereof I affix my signature in presence of two witnesses.

MATTHIAS GATES.

Witnesses:

JOHN MENDENHALL,
JOHN G. BRIGHT.
